UNITED STATES PATENT OFFICE.

MIKE MINTZ, OF ROCK ISLAND, ILLINOIS, ASSIGNOR TO GEARLESS AUTOMATIC PUMP COMPANY, OF ROCK ISLAND, ILLINOIS, A CORPORATION OF ILLINOIS.

DIAPHRAGM-VALVE.

1,203,551.

Specification of Letters Patent. Patented Oct. 31, 1916.

Application filed February 24, 1911. Serial No. 610,843.

To all whom it may concern:

Be it known that I, MIKE MINTZ, a citizen of the United States, residing at Rock Island, in the county of Rock Island and State of Illinois, have invented new and useful Improvements in Diaphragm-Valves, of which the following is a full, clear, concise, and exact description, reference being had to the accompanying drawing, forming a part of this specification.

My invention relates to improvements in diaphragm valves and has for its object the production of a device that may be used in connection with any system requiring such valves, and one that is especially adapted for use in connection with air compressors and vacuum pumps.

One of the objects of my invention is to provide a device in which the use of packing between the diaphragm and the shell may be dispensed with.

A further object is the production of means whereby the strain on the diaphragm when under pressure may be distributed over the entire disk.

A further object is the production of a device in which an improved seat for the valve is provided thus assuring accurate adjustment of the valve.

These and such other objects as may hereinafter appear are attained by my device, an embodiment of which is illustrated in the accompanying drawing, in which—

Figure 1 represents a sectional elevation of my device; Fig. 2 represents a sectional view on the line 2—2 of Fig. 1, looking in the direction indicated by the arrows; Fig. 3 represents a sectional view on the line 3—3 of Fig. 2, looking in the direction indicated by the arrows.

Like numerals of reference indicate like parts in the several figures of the drawing.

Referring now to the drawing, A represents a diaphragm case comprising an upper shell or covering 4 and a lower cup-shaped shell 5 with a diaphragm 6, clamped between the edges of said shells. The lower shell is provided with a circumferential flange 7 having on its upper face a shoulder 8, extending entirely about the flange and the upper shell 4 is also provided with a corresponding flange 9 preferably turned down at its edge as shown at 10 and adapted to fit against the end of the shoulder 7.

The under face of the flange 9 is provided with a circumferential groove or depression 11 registering with the bead or shoulder 8 on the lower flange.

The diaphragm in my preferred construction is formed from a sheet of copper and having a circumferential bead 12 adapted to fit within the groove 11 and be engaged by the shoulder 8, thus insuring a tight joint without the necessity for packing.

A plurality of screws 13 pass through the flanges 7 and 9 and the outer edge of the diaphragm 6. Ordinarily when packing is used the strain on the diaphragm would all come on the portion back of the screws, whereas, in this construction, it is distributed equally on the entire outer circumference of the diaphragm.

The center of the diaphragm is bored or cut away and a reinforcing plate 14 inserted, provided with a central opening 15. The under side of the plate about the opening is cut away in the shape of a spherical segment forming a valve seat 16. An inlet opening 17 is provided in the base 18 of the lower shell and a valve stem 19 is screwed therein. Seated on or in the top of the stem 19 is a spherical valve 20 adapted to fit within the seat 16. The screw connection between the stem and the base is made loose so as to permit a slight rocking movement of the stem and in the event that the valve is not perfectly centered, this slight movement of the post brings the ball to the center of the opening when it seats, thus closing it tightly.

The valve stem or post 19 may be held from backing down into the threads by locking it in any well known manner as for instance, by simply bending in the top edge of the threads of the casing at 21 so that they press into the opening 22 which communicates with a channel 23 in the lower end of the post, opening into the chamber 24.

Pipes 25 connect the interior of the diaphragm chamber A' below the diaphragm with the compressor pumps (not shown) and a pipe 26 is screwed into the top casing at 27 making an open communication through the channel 28 from any suitable regulator to the upper chamber A' above the diaphragm.

From the upper shell 4 a tube 29 extends, communicating with the interior A', to which may be connected the pipe 30 leading

2
to the storage tank or reservoir (not shown).
As the air forced through the valve is often impregnated with oil which collects 5 upon the under side of the diaphragm and runs down to the bottom of the chamber A^2 , I provide means for withdrawing this material by forming a channel 31 at the lowermost portion of the chamber and communicating with a valve controlled passage 10 32 through which the oil is carried off.

The operation of my device is extremely simple; air is pumped through the pipes 25 and the chamber A^2 through the valve opening 15 into the chamber A' and through the pipe 30 into the tank or reservoir, the regulator being in open communication with the chamber A' through the pipe 26. When the pressure within the tank reaches a predetermined point, the regulator automatically operates to shut off the motor operating the pumps and at the same time opens 20 the valve 33. The pressure below the diaphragm at once drops and the diaphragm is forced downwardly by the pressure within the upper chamber, closing the valve opening 15. This valve remains closed until the pressure within the tank falls below a predetermined point when the regulator 25 automatically starts the motor operating the pumps and closes the relief valve. The increase of pressure within the lower chamber at once serves to open the valve 15 and the operation is repeated.

35 It will be noted that the diaphragm disk 6 is tightly placed in position against the valve seat, and I find it often advisable to slightly raise the valve stem 19 to insure such setting at normal position. This form 40 of assembling makes the diaphragm the equivalent of a spring whereby the diaphragm will be closed where the pressure is equal in the chambers, A' , A^2 . Of course as soon as the air is released from the 45 chamber A to A second, the pressure on the upper face of the diaphragm will close it and in the event that the release valve is not operated quickly, the spring in the diaphragm itself will close the valve. It is 50 evident that this spring is practically formed by reason of the diaphragm being tightly held between the edges of the casing by means of the bead, shoulder and groove. Attention is also called to the fact that by 55 reason of the spherical valve seat 16 and the spherical stem, the accurate closing of the valve is insured at all times whether a rocking stem is used or not; for instance, in the ordinary cone valve seat or what is 60 termed the needle point valve, the valve would have to come to a perfect seat or fail

in its purpose while with this construction the diaphragm disk should be greatly depressed on one side and yet by reason of the spherical shape of the seat, the valve 65 would close just as tightly and hold the air perfectly.

This device is extremely simple in construction in spite of which, however, it gives great durability to the diaphragm, and insures a quick and accurate seating of the valve.

The relief valve, herein referred to but not claimed, switch and other features, are made the subject of separate applications, 75 filed under even date herewith Serial Numbers 610,642 and 610,844 and are not explained in detail in the present application.

While I have illustrated an embodiment of my device, it is understood, of course, 80 that other modifications may be made without departing from the spirit of my invention.

I claim:

1. In a device of the class described, the 85 combination with a casing comprising an upper shell and a lower shell, said lower shell having an axial screw threaded opening therein, of a valve member adjustably threaded in said opening, and having an 90 axial opening therethrough leading from the interior of the casing and provided with a seating portion at its upper end, of a diaphragm held between said shells and provided with an apertured member having 95 a seating portion coöperating with the first said seating portion.

2. In a device of the class described, the combination with a casing comprising an upper shell and a lower shell, said lower 100 shell having an axial screw threaded opening therein, of a valve member adjustably threaded in said opening, and having an axial opening therethrough leading from the interior of the casing and provided with 105 a seating portion at its upper end, of a diaphragm held between said shells and provided with an apertured member having a seating portion coöperating with the first 110 said seating portion, said casing having a passage therethrough for connection with a pipe line, said passage being in communication with said axial opening through said screw threaded opening.

In witness whereof, I have hereunto subscribed my name in the presence of two witnesses.

MIKE MINTZ.

Witnesses:

NELLE COLLINS.

It is hereby certified that in Letters Patent No. 1,203,551, granted October 31, 1916, upon the application of Mike Mintz, of Rock Island, Illinois, for an improvement in "Diaphragm-Valves," an error appears in the printed specification requiring correction as follows: Page 2, line 77, for the serial number "610,844" read 610,644; and that the said Letters Patent should be read with this correction therein that the same may conform to the record of the case in the Patent Office.

Signed and sealed this 28th day of November, A. D., 1916.

[SEAL.]

F. W. H. CLAY,
Acting Commissioner of Patents.
